REFRIGERATING SYSTEM

Glenn Muffly, Scarsdale, N. Y.

Application August 17, 1931, Serial No. 557,476

17 Claims. (Cl. 62—116)

The invention relates to refrigerating systems, and it has particular relation to a refrigerator of the mechanically operated type.

The invention in some respects constitutes an improvement over my co-pending application for patent on a refrigerator, Serial No. 455,741, filed May 26, 1930, and in some respects is related to my Patent 1,787,209 issued December 30, 1930.

The principal objects of the invention are to provide a refrigerator cabinet in which a refrigerating system is so mounted that it may be easily handled and manipulated by a single workman without special equipment, and the system readily installed, removed, and transported; to provide a refrigerator of this character in which the refrigerating system is movably connected to a wall of the cabinet other than the front wall thereof, whereby the system can be moved downwardly into the refrigerated space and the heat dissipating part of the system disposed in such position that it is accessible through the door of the refrigerator; to provide a refrigerator in which the heat dissipating part of the refrigerating system is cooled in a novel and efficient manner; to provide a refrigerator in which a refrigerating system is provided with a thermal element which is adjustable with respect to the heat absorbing part of the system; to provide a refrigerating system in which clock control means are utilized for starting and stopping the system and maintaining it out of operation for a predetermined period of time; to provide a refrigerating system of the last mentioned character having control means for temporarily rendering the clock control inoperative if this is desired; to provide a refrigerator cabinet having a refrigerating system therein which can bodily be removed from the cabinet through the door thereof, or bodily moved into the refrigerated space of the cabinet where various parts of the system will be accessible for adjustment and the like; and to provide a refrigerator having a drip pan and receptacle therefor which are constructed and arranged in the refrigerator cabinet in a novel manner.

For a better understanding of the invention, reference may be had to the accompanying drawings forming a part of the specification, in which:

Figure 1 is a fragmentary elevational view of a refrigerator constructed according to one form of the invention, with parts broken away for the purpose of illustrating the interior of the refrigerator;

Fig. 2 is a cross sectional view on a larger scale, taken substantially along line 2—2 of Fig. 1;

Fig. 3 is a cross sectional view on a larger

scale taken substantially along the line 3—3 of Fig. 2;

Fig. 4 is a cross sectional view taken substantially along line 4—4 of Fig. 3;

Fig. 5 is a cross sectional view on a larger scale, taken substantially along line 5—5 of Fig. 1;

Fig. 6 is a cross sectional view on a larger scale taken substantially along line 6—6 of Fig. 5;

Fig. 7 is a cross sectional view taken substantially along line 7—7 of Fig. 6;

Fig. 8 is a side view partly in cross section taken substantially along line 8—8 of Fig. 6;

Fig. 9 is a cross sectional view on a larger scale, taken substantially along line 9—9 of Fig. 1;

Fig. 10 is a diagrammatic illustration of an electrical circuit utilized in the refrigerating system;

Fig. 11 is a fragmentary view taken interiorly of the refrigerator cabinet, illustrating a modified form of drip pan and receptacle therefor;

Fig. 12 is a fragmentary view of a modified form of clock controlling mechanism that may be employed in the system;

Fig. 13 is a cross sectional view on a larger scale taken substantially on the line 13—13 of Fig. 12;

Fig. 14 is a diagrammatic view with certain parts in cross section, illustrating the connection between the condenser and evaporator.

Referring to Fig. 1, a refrigerator cabinet is indicated generally at 10 which comprises a body 11, a covering element 12 for the top of the cabinet, and a pivoted door 13 at the front of the cabinet. Interiorly of the cabinet, conventional shelves 14 are supported in a refrigerated space 15 provided in the lower region of the cabinet.

Referring now to Fig. 5 particularly, that portion of the cabinet defining the refrigerated space 15 is provided with walls 16 composed of insulating material, the upper edges of which are 40 surrounded with a frame work indicated at 17. The inner and outer surfaces of the insulating material 16 and the frame 17 are lined in a conventional manner with suitable covering material indicated generally at 18. The frame 17 is inclined at its upper and inner edge as indicated at 19 for the purpose of providing a support for a base 20 upon which the refrigerating system is mounted. A sealing element 21 preferably is disposed between the frame 17 and the base 20 to seal the interior of the refrigerator or the refrigerating space. The outer peripheral portion of the base 20 has a frame 22, while the intermediate portion thereof is composed of insulating material indicated at 23, although it 55

should be understood that any suitable material may be used for the base. A U-shape bracket 24 secured to the lower surface of the base 20 and at its rear edge, as indicated at 25, extends 5 downwardly into the refrigerated space adjacent the rear wall of the cabinet and includes a laterally directed portion 26 which is pivotally seated in hinge elements 27 secured as indicated at 28 to the rear wall of the cabinet.

10 The front edge 22 of the base 20 is inclined slightly to the vertical as indicated at 29 in a manner substantially complementary to an inclined rear edge surface 30 formed on a transversely extending member 31 forming a part of 5 the cabinet and which is disposed at the upper edge of the door 13. The front edge portion of the base 20 is adapted to be supported by a latch bolt 32 slidably disposed in a channel member 33 secured in the lower portion of the frame 10 22 at the front edge of the base 20. This bolt is normally urged toward the member 31 by a spring 34 encircling the rear part of the bolt and engaging the rear wall of the channel 33 at one end, and a flanged portion 35 on an intermediate part of the bolt at the other end. The front end of the bolt, when the base 20 is in position as shown by Fig. 5, projects into a keeper 36 attached to the member 31. At one 0 point the lower wall of the channel 33 is apertured as indicated at 37, which permits the insertion of a screw driver into the channel 33 in front of the flanged portion 35 on the bolt, for the purpose of moving the flanged portion and bolt rearwardly until the bolt is free of engagement with a keeper 36. For the purpose of positively preventing downward movement of the base 20 about the hinged connections 26 and 27, should the bolt 32 become broken, for example, a screw 39 projects through an opening in the channel 33, upwardly through the frame 22 at the front edge of the base 20, and is threaded into a plate 40 secured as indicated at 41 to the upper surface of the member 31 forming a stationary part of the cabinet. The screw in its operative position, is disposed immediately to the rear of the flanged portion 35 of bolt 32, and hence positively prevents accidental movement of the bolt rearwardly and disengagement thereof with the keeper 36. A resilient element 42 is disposed between the plate 40 and the upper surface of the member 31 for sealing the space above the base 20 against air circulation to or from the space below it.

The weight of the front portion of base 20 and parts mounted thereon will be supported by the screw 39 or by the bolt 32 or by both according to how tightly screw 39 is screwed home.

A heat absorbing unit or evaporator 45, is suspended from the lower surface of the base 20 and comprises the usual convolution of coils 46. The outlet end of the evaporator coil indicated at 46' extends through the base 20 and is connected to the intake side of a compressor located above the base, while the inlet end of the evaporator is connected to an expansion device which is in turn connected through the base to a condenser also mounted at the upper side of the base. The condenser, compressor, and associated apparatus above the base 20 presently will be described.

10 The evaporator coil 46 serves as a support for ice trays 47, and is supported on a plate 48 having vertical side portion 49, secured at their upper edges to the lower surface of the base 20. The open front end of the evaporator unit is substantially closed by a vertical plate 49 having a flange

50' at its upper edge secured to the lower surface of the base 20 by means of the previously mentioned screw 39. The flange 50' normally covers or seals the openings 37 in the lower wall of the channel 33.

The wall 49 is provided with suitable openings 50 by means of which the ice trays 47 may be removed and inserted into the evaporator unit. A cover 51 pivoted as indicated at 52 to the plate 49 immediately above the opening 50, normally closes the latter although it can be readily moved about its pivot when it is desired to remove the ice trays. The lower edge of the plate 49 is integrally connected to a drip and baffle pan 53 that tapers rearwardly to a point in proximity to a rear corner of the refrigerator cabinet. At this point a drip cup 54, which is adapted to receive moisture dripping from the evaporator, is supported on the shelf 14. The rear end of the drip pan 53 terminates in a substantially vertically projecting portion 55 which is provided with openings 56 adjacent its upper edge adapted to be releasably engaged with projecting end portions 57 of the hinge elements 27. It is apparent that the baffle is secured at its front and rear ends to stationary parts of the cabinet, by means of the screw 39 threaded into the plate 40, and the hinge elements 27 connected to the rear wall of the cabinet. Hence the baffle would catch any falling part of the refrigerating system and prevent possible injury to the cabinet lining, to dishes contained in the cabinet or to a person removing or placing food in the refrigerated space below the baffle.

At its upper side, the base 20 supports a motor 35 60 and a compressor 61 which are secured to the base by means of bolts 62. A discharge pipe 63 extending from the compressor 61 is connected to an upper coil of a condenser 64 located at the rear edge of the base 20 and supported thereby. 40 As best shown by Figs. 5 and 9, the condenser comprises end plates 65 and 66 which respectively have slots 67 at their front and rear edges, adapted to support front and rear, upwardly converging rows of condenser tubes. In one method of 45 construction each opening initially has a front straight portion 68 through which a tube of the condensing unit is adapted to pass, which opening terminates in a circular portion adapted to receive the tube and retain it in position. After 50 the tube is so positioned, a lip 69 which initially has been turned into a horizontal position, is reverted to a vertical position and in the latter position prevents movement of the tube outwardly through the slot. The condenser tubing is preferably supplied with fins 70.

A trough shaped element 71 attached to the parts 65 and 66 makes the assembly more rigid and directs air flow over the tubes. The condenser is so positioned on the rear of the base 60 20 that the rear row of tubes is disposed rearwardly of the plane of the rear surface 18 of the refrigerator cabinet. Vertically extending corner posts 75 and 76 at the rear of the refrigerator cabinet adjacent to its sides are provided as part 65 of the frame structure and to maintain the cabinet spaced from any room wall to which the rear of the cabinet is disposed in adjacent relation. This space between the rear wall of the cabinet and the wall of the room adjacent thereto, permits cool air from the lower part of the room to flow upwardly between the rear wall of the cabinet and the room wall to replace air that has been heated by the condenser and thus caused to flow upward. The trough 71 project- 75

ing as it does downwardly between the convolutions of the condenser, constitutes a guide for deflecting the flow of cool air around the tubes of the condenser. For facilitating this manner 5 of cooling the condenser, the cover portion 12 at the top of the refrigerator cabinet, is provided with a flue 78, at the rear edge thereof, which is located mainly above the condenser. Air surrounding the motor 60 and the compressor 61 is 10 also caused to circulate due to its thermal expansion, the heated air passing rearward and upward through the flue 78 and cool air coming in at the front of the cabinet through the louvers 78'.

15 The condenser 64 is connected to the evaporator 46 by means of a capillary tube 69' extending through the rear of the base 20 as shown particularly by Figs. 2, 9 and 14. The condenser end of the tube 69' is provided with an elongated, fine mesh screen 70' which has its outer end retained in an opening 71' formed in the flare union part 72' which coacts with the flare union nut 73' at the end of the condenser tube. One end of the tube 69' extends through an opening in the union part 72' and projects within the screen 70'. It, of course, should be understood that the tube 69' is soldered or brazed to the union part 72'.

20 Below the base 20 the tube 69' has a coil portion 74' and then projects through a flare union 25 75' which coacts with the flare nut 76' on the end of the evaporator coil 46.

25 It should be understood that the refrigerating system includes the motor 60, compressor 61, condenser 64 and evaporating unit 45 and that the first three mentioned parts of the system are mounted on the upper side of the base 20 while the evaporator 45 is suspended from the lower side of the base 20. Hence the system moves with the base 20, either when the latter is pivoted about the hinge connections 26 and 27 30 or is bodily removed from the refrigerator. When it is desired to inspect the system or make repairs thereon, the screw 39 is removed, and then the drip pan is disengaged from the hinge connections 27 and removed from the cabinet. Also the shelf 14 and drip cup 54 are removed from the cabinet. Then the latch bolt 32 is moved rearwardly by a screw driver or other suitable tool, until it is disengaged from the keeper 35 40 and then the base 20 with the system mounted thereon is allowed to move downwardly about the hinge pivot 26 into the refrigerated space until the evaporator rests against the rear wall 45 of the cabinet. This movement positions the motor, compressor and condenser at the door opening where ready access may be had to such parts of the system. A single workman can bodily remove the base and system through the door 50 way, by means of handles 80 and 81 provided on the upper side of the base and when the base and system have been moved downwardly into the refrigerated spaces, the handles serve as a means for manually lifting the base and disengaging hinge element 26 from hinge elements 27, 55 whereupon the base and system can be withdrawn through the doorway. Re-positioning the base and system in the cabinet is effected in a reverse manner.

60 70 The electrical means for controlling the operation of the system now will be described. Referring to Figure 9, this electrical means includes a clock 85 mounted in the front wall of the refrigerator cabinet above the door 13, and a thermally responsive switch mounted in a box 86

secured to the upper side of the base 20 adjacent the motor 60. As best shown by Figures 3 and 4 the thermally responsive switch includes an expansive bellows 87, and a capillary tube 89 which extends from one end of the bellows toward the 5 rear of the refrigerator cabinet along the base 20 at its upper side, (Fig. 2), and then downwardly between the frame 22 and the cabinet. Then the tube extends along the inner side of one of the walls 49' at the side of the evaporator unit to 10 toward the door 13, then is looped about a pin 91 secured in said wall 49', and then extends along an arm 92 mounted on the pin 91, to a point near the door 13. At its forward end, the tube 89 terminates in a bulb 93 secured to the forward 15 end of the arm. This bulb is partially filled with a volatile liquid of a character conventionally used in thermal switches, and is adapted to be disposed in variable positions with respect to the evaporator coils 46, from which it follows that the vapor 20 pressure of the fluid in the bulb will be affected by the position of the bulb with respect to the evaporator coils. The forward end of the arm 92 has an offset portion 94 which, as best shown by Fig. 1, 25 extends laterally beyond the end of the pivoted cover 51 and the plate 49, and then terminates in a handle 95 accessible upon opening the door of the refrigerator, for moving the arm 92 and consequently the bulb 93 vertically with respect to the evaporator coils. Spaced depressions 96 30 35 formed in the front edge portion of the plate 49' are adapted selectively to cooperate with a projection 97 on the arm 92 for securing the arm in any of its adjusted positions.

Referring again to Figs. 3 and 4, the inner end 35 of the bellows 87 is provided with a plate 100 having a central projection 101 which retains one end of a spring 102 that at its other end abuts a collar 103 adjustably maintained in position by a screw 104 threaded through the adjacent wall 40 of the switch box. Also the plate 100 is provided with a projection 105 pivoted upon a pin 106 secured at its ends to inwardly projecting lips 107 of the switch box. Hence upon expansion or contraction of the bellows, the plate 100 pivots about the pin 106. The screw 104 serves as a means for adjusting the tension of the spring 102 and consequently permits a variable resistance to expansion of the bellows 87 and hence a variation in 45 the thermal control. The upper edge of the plate 100 also is provided with a bifurcated, non-conducting projection 110 which has a pin 111 projecting through an elongate slot 112 formed in a switch operating arm 113 disposed between the 50 legs of the projection. The outer end of arm 113 is of cylindrical shape as indicated at 114 and a spring 115 encircling this portion of the arm, abuts at its lower end a collar 116 slidably movable on the arm. The outer surface of the bifurcated arm 110 is substantially cylindrical in shape and when 55 the arm is moved, it is capable of moving the collar 116 against the spring. The outer end of the spring abuts a second collar 118 which is rigidly mounted on the arm, and the outer end of the arm is provided with a roller 119. When the bellows contracts from its expanded position as shown in Fig. 4, the arm 110 is moved toward the right and when the pin 111 has moved to a certain 60 position the spring 115 acts to move the roller 119 and arm 113 counterclockwise into the position shown in broken lines 120. Conversely when the bellows expands the pin 111 is moved to the left, and at a certain point in such movement, the 65 70 75

spring acts to move the roller 119 back into its full line position as shown by Fig. 4.

When the roller 119 is in its full line position, it engages a pair of electrical contact elements 121 and 122, as best shown by Fig. 3, which are secured to an insulating element 124 projecting downwardly through the upper wall of the switch box 86, one wall 125 of the insulating element serving as a stop when the roller 119 moves into its broken line position as shown by Fig. 4. Electrical conductors 126 and 127 projecting above the upper surface of the insulating element 124 are respectively secured to the contact element 121 and a conductor 130 extending through a wall of the switch box. The element 122 in turn is connected to a second conductor 131 which also extends through the switch box wall and when the plates 121 and 122 are bridged by the roller 119, the conductor 126 is electrically connected to the conductor 131 and an electrical circuit through the switch box can be completed. Conductors 130 and 131 extend to the motor 60 which preferably has starting and running windings, the former of which is automatically rendered inoperative when the speed of the motor has reached a predetermined number of revolutions per minute.

As best shown by Fig. 9, an electric cable 135 extends through the rear of the refrigerator cabinet adjacent an edge of the base 20, and comprises conductors 136 and 137, which lead directly to the clock 85. A flexible branch conductor 138 connected to conductor 137 extends laterally toward the switch box 86 and as best shown by Fig. 5 is connected to a conventional type of plug 139 having two terminals adapted to engage the terminals 126 and 127 on the switch box shown by Fig. 3. Another flexible conductor 140 extending from the plug 139 extends to the clock 85, as shown by Fig. 9.

Referring now to Figs. 6, 7 and 8, the clock 85 is provided with a synchronous motor 142 directly connected to the conductors 136 and 137 and it therefore operates continuously. Conductor 136 also is connected to binding post 144 mounted on an insulator 143 which is supported by the clock frame 142, and from this connection, a wire resistance 145 extends upwardly and is connected at its upper end, as indicated at 146, to a second similar binding post 146 on an insulator 147. A conductor 148 extending from connection 146 is connected to a commutator brush 150 by means of a bolt 149 securing the brush on an insulating block 151. The latter is pivotally mounted on a pin 152 projecting from frame 142 of the clock. A second commutator brush 153 shown in Figs. 10 and 13, is secured to the insulating block 151 by a bolt 153', which also connects this brush to electrical conductor 140 extending from the female connector 139. The commutator brushes are mounted on the insulating element 151 in insulated relation and their free ends are adapted to have wiping engagement with a metal commutator sleeve 154 secured on an insulating element 155, which engagement is assured by virtue of the fact that the brushes are made of spring stock. The element 155 is mounted on a shaft 155' which is operatively connected to and driven by the synchronous motor 142. The metal sleeve 154 extends about a major portion of the periphery of insulating element 155 and is adapted to bridge the ends of the commutator brushes 150 and 153 and complete the circuit between electrical conductors 136 and 140. Between the ends of the metal sleeve 154 insulating element 155 has a V shaped

tooth 157, and when this part of the commutator engages the brushes 150 and 153, the ends of the brushes are insulated from each other. Notching the exposed part of the insulating element in this manner to provide the tooth, insures a snap action of the commutator brushes when they leave the metal sleeve 154 and a snap action thereof when they move past the tooth, thereby minimizing electrical arcs between the brushes and sleeve. It will be noted that the metal sleeve 154 has an inwardly directed radial end portion 158 and consequently when the commutator has so moved that the tooth moves past the commutator brushes, they will snap into engagement with such radial portion of the metal sleeve by their own spring action and be electrically connected.

An arm 160, also pivotally mounted on the pin 152 is connected by a pin 161 to the insulating element 151 and accordingly when either of these elements is moved about the pivot 152, both elements will be moved together. A part of arm 160 has a catch 162 which is adapted to engage under a struck out lip 163 formed on a bimetallic element 164 extending between insulators 143 and 147 and retained by notches in said insulators. The bi-metallic element is of such character, that when the resistance 145 becomes excessively heated the intermediate portion of the bi-metallic element will be moved toward the resistance which will cause the struck out lip 163 to disengage from the catch 162. When such disengagement occurs a spring 165 connected at one end as indicated at 166 to a stationary part of the clock, and at its other end to the arm 160, will cause the arm and insulating element 151 to turn about the pivot 152, in a counterclockwise direction, which will result in a movement of the commutator brushes 150 and 153 away from the commutator 154. For the purpose of manually moving the bi-metallic element 164 in the manner just described, an arm 168 is pivotally mounted on the clock frame 142 as indicated at 169, and it is provided with a lip portion 170 disposed adjacent the bi-metallic element, which, upon turning the arm in a clockwise direction, moves the bi-metallic element in the manner previously mentioned. The opposite end of the arm 168 indicated at 172 is disposed adjacent to a frusto-conical element 173, rigidly secured on a plunger 174, projecting towards the front wall of the clock casing and which terminates in a button 175 projecting through such wall. Inwardly of the front wall of the clock casing the button 175 is provided with a shoulder 176 adapted to prevent a complete movement of the button outwardly through the wall, and which also serves as an abutment for one end of a helical spring 177 encircling the plunger interiorly of the clock casing. The opposite end of the spring engages a bracket 178, stationarily mounted in the clock casing and which serves as a means for limiting movement of the frusto-conical element 173. When the button 175 is pushed inwardly, it is apparent that the portion 172 of arm 168 will be engaged by the conical surface of member 173 and hence will be so moved that the arm 168 will be turned in a clockwise direction about the pivot 169 and hence the lip 170 will be moved into engagement with bi-metallic element 164 for the purpose of disengaging the lip 163 from catch 162.

For re-engaging the catch 162 with the lip 163 on the bi-metallic element, after it thus has been disengaged by pushing the button 175 or otherwise, a second and like button element 180 is pro-

vided which similarly has a frusto-conically shaped element 181 which is adapted to engage an extension of arm 160 and thus move the arm clockwise and the catch 162 into engaging relation with the lip 163.

Assuming that the metal commutator sleeve 154 electrically connects commutator brushes 150 and 153, and that the bellows is expanded and therefore the roller 119 electrically connects the terminals 121 and 122 in switch box 86, an electrical circuit is completed through the motor 60 and the refrigerating system will operate to reduce the temperature in the refrigerator. When this temperature has been reduced to a predetermined point, the vapor pressure in the bellows, will be sufficiently reduced to allow the bellows to collapse, which will cause the roller 119 to move into its inoperative position thereby opening the motor circuit. When the temperature of the refrigerator is raised sufficiently, it is apparent that the bellows 87 will again expand and complete the circuit through the motor, whereupon the refrigerating system again will operate to reduce the temperature in the refrigerator. If for any reason the motor becomes overloaded, the excessive current passing through the resistance 145 will sufficiently heat this element that the bi-metallic element 164 will bend toward the resistance and disengage the lip from the catch 162 whereupon the spring 165 will move the insulating element 151, and the commutator brushes will be moved out of engagement with the commutator, whereupon the circuit through the motor will again be interrupted. Assuming however that no excessive loading of the electrical circuit occurs, manual interruption of the circuit may be effected by pushing button 175, which will cause the arm 168 to turn about pivot 169 and in turn the lip 170 on the arm to move the bi-metallic element toward the resistance 145 and the lip 163 out of engagement with the catch 162 and then the spring 165 will act to move the commutator brushes way from the commutator and deenergize the motor.

Assuming that the commutator brushes are in contact with the metal sleeve 154, disengagement of the brushes with the metal sleeve will automatically occur at a predetermined time by rotary movement of the commutator by the clock motor 142. Then the commutator brushes will engage the tooth 157 on the insulating element 155 of the commutator and be maintained out of engagement with the metal sleeve 154 until the clock motor has rotated the commutator into such position that the tooth moves past the ends of the commutator brushes when the latter, due to their own spring action, will engage the radial end 158 of the metal sleeve on the commutator. Hence during a predetermined interval of time, preferably at a time when most electrical energy is being used by a community, the clock will so function that the commutator brushes are engaging the insulating element on the commutator and the motor in the refrigerator will be prevented from operating for a predetermined period of time regardless of temperature conditions within the cabinet.

From the above description, taken in connection with Fig. 10 illustrating the electrical circuit, it should be understood that the thermally responsive switch located in switch box 86 serves as a means for automatically energizing and de-energizing the motor depending on the temperature in the refrigerator. It is also apparent that independently of the thermal control, the clock

will interrupt the electrical circuit through the motor if it is completed through the thermally responsive switch, at a predetermined time and for a predetermined interval of time. Also it will be understood that regardless of the operation of the clock, the motor circuit may be opened by manual operation of push button 175 which separates the commutator brushes from the commutator. Also, it will be understood that if the electrical circuit is so interrupted by pushing button 175, that it may be again completed insofar as the clock is concerned, by pushing button 180 which will cause the commutator brushes again to be brought into contact with the commutator and retained in their positions by the catch 162 engaging the lip 163 on the bi-metallic element. Thus if it is desired to prevent operation of the refrigerating system at times when the thermally responsive switch is acting to complete the electrical circuit through the motor, it is only necessary to push button 175 and the system may be de-energized for any period of time required whereafter it again may be completed or energized by pushing button 180.

For the purpose of preventing interruption of the system by operation of the clock, when for example it is desired to secure or maintain a low freezing temperature in the refrigerator during the time the clock normally would prevent energization of the motor, a modified arrangement shown in Figs. 12 and 13 is provided and in this construction an insulating element 190 is rotatably mounted on the commutator shaft 155' and connected to the shaft by means of an arcuate slot 191 in the insulating element, which cooperates with a pin 192 secured to collar 192' rigid with the shaft. By means of this arrangement a partial rotary movement of the insulating element with respect to the shaft 155', within the limits of the length of the slot 191, can be secured. Normally however, the pin 192 is located at the clockwise end of slot 191 and consequently shaft 155' will rotate the insulating element constantly. Assuming that the commutator brushes 150 and 153 are about to engage the exposed insulating tooth 157 on the insulating element 190, or that they are in engagement with the insulating tooth, and it is desired to prevent interruption of the electrical circuit through the motor it is only necessary to rotate the insulating element 190 with respect to the shaft 155', and then the commutator brushes will be relatively moved over the exposed tooth 157 of the insulating element and brought into engagement again with the metal sleeve thereon. For the purpose of providing a manual means for so rotating the insulating element with respect to shaft 155', an arm 193 is provided which has a projecting end portion 194 adapted to engage a pin 195 on the insulating element. Arm 193 is slidably mounted in a bracket 195 secured to the clock casing interiorly thereof, and at its lower end is pivotally connected to a bell crank lever 196, which in turn is pivotally connected as indicated at 197, to the wall of the clock housing. The opposite end of the bell crank engages the frusto conical element 181 and normally is maintained in such position that the projecting end portion 194 of arm 193 is disposed out of the path of movement of pin 195, by means of a spring 198 connecting the bell crank to the wall of the clock housing.

From the above description it is apparent that if the clock motor has so moved the commutator that the commutator brushes are about to engage the exposed part of the insulating element on the

commutator, or that the commutator brushes are in engagement with the exposed insulating element, and it is desired to prevent engagement of the commutator brushes with the insulating element or reconnect the commutator brushes with the metal sleeve of the commutator, it is only necessary to push button 180 whereupon the insulating element 190 will be rotated within the limits of the slot 191 and the brushes again brought into engagement with the metal sleeve at 158. Then the insulating element will remain in a stationary position until the clock so operates that the pin 192 reengages the insulating element at the clockwise end of the slot 191.

15 When a downward movement of the base 20 in the manner previously described has partially occurred the connector 139 is removed from the switch box 86 although it should be understood that an automatic disengagement of the connector from the switch box may be effected when the base 20 is moved downwardly and that an arrangement may be provided whereupon the plug will automatically reengage the switch box when the base again is moved into its operative position.

15 According to Fig. 11 the drip pan 53 is provided with a pair of brackets 200 and 201 having flanged portions 202 and 203 which serve as guides and retaining means for the drip cup 54. When it is desired to remove the drip cup 54 it is only necessary to move it toward the door 13 of the refrigerator and beyond the end of the bracket members 200 and 201. This arrangement is desirable because it provides a means separately of the shelf 14 in the refrigerator, for supporting the drip cup.

It is apparent that the thermal control of the refrigerator may be adjusted by adjusting the tension on the spring 102 in the switch box as shown by Fig. 4 by moving the screw 104 through the wall of the switch box, and also that a thermal adjustment for temporary quick freezing or the like, may be made by moving the arm 92, as shown by Fig. 2, with respect to the evaporating unit 46 which disposes the bulb 93 in variable positions with respect to the evaporator unit. It is also apparent that movement of the bulb 93 and arm 92 in this manner may easily be made by opening the door 13 of the refrigerator and manually moving the arm in the desired manner.

50 Formal changes may be made in the specific embodiment of the invention described without departing from the spirit or substance of the broad invention, the scope of which is commensurate with the appended claims.

I claim:

1. A refrigerator cabinet having a refrigerated space, a refrigerating system including a support swingably mounted within said cabinet having heat absorbing means on one side and heat dissipating means on the other side, said support being swingable about an axis adjacent the rear wall of said refrigerated space so as to bring the system into operative position with said heat absorbing means located in said refrigerated space and said heat dissipating means outside of said refrigerated space.

2. A refrigerator cabinet having a refrigerated space therein and an opening through which said refrigerated space is accessible, a refrigerating system pivotally mounted adjacent the rear inner wall of said cabinet on a substantially horizontal axis, and including heat absorbing means and heat dissipating means, said system being insertable through the opening and being swing-

able into horizontal operative position with said heat absorbing means located in said refrigerated space and said heat dissipating means located outside of said space.

3. A refrigerator cabinet having a refrigerated space therein, a door opening through which said space is accessible, and a second opening above said refrigerated space, a removable wall section for closing said second opening and being removable through the door opening, a hinge part attached to the inner rear wall of said refrigerated space, a hinge part attached to said removable wall section and adapted to detachably engage the first hinge part for coaction therewith, heat absorbing means mounted on said removable wall section on its refrigerated space side, heat dissipating means including a condenser, mounted on the opposite side of said wall section, said condenser being so positioned that when the wall section is hinged into position to close said second opening, said condenser will be positioned above and adjacent to the rear wall of said refrigerator space.

4. In a refrigerator cabinet having a refrigerated space, a door opening and a unit opening, a removable refrigerating system, and detachable means on said cabinet and refrigerating system respectively for pivotally supporting the latter in the cabinet, said system being adapted to be pivoted into operating position by a forward and upward movement of said system from the interior of said refrigerated space and partially through said unit opening.

5. In a refrigerator cabinet having a refrigerated space therein, a refrigerating system including heat absorbing and heat dissipating means adapted to be pivotally attached to said cabinet adjacent the rear wall thereof, said system being swingable so as to bring it into operative position with said heat absorbing means located in the upper portion of said refrigerated space and said heat dissipating means located outside of said space.

6. In a refrigerator cabinet having a refrigerated space therein, and a door for access to said space, a refrigerating system including heat absorbing and heat dissipating means adapted to be pivotally supported by said cabinet adjacent the rear wall thereof, said system being insertable through said door for such pivotal attachment and then swingable so as to bring it into operative position with said heat absorbing means located in the upper portion of said refrigerated space and said heat dissipating means located outside of said space.

7. A refrigerator cabinet, a removable refrigerating system installed in said cabinet for the purpose of cooling the same, a latch designed to hold said system in its operating position in said cabinet, a baffle in said cabinet adjacent to the heat absorbing portion of said system, and a common means for securing said baffle in said cabinet and locking said latch so that said unit is securely locked in position.

8. A refrigerator cabinet, a refrigerating system removably installed in said cabinet to cool the same, a hinge part attached to the rear inner lining of said cabinet, and a hinge part attached to said system, said hinge parts being cooperative for the purpose of locating said system in said cabinet and guiding it into operative position while it is being installed in said cabinet.

9. A refrigerator cabinet, a refrigerating system removably installed in said cabinet by first inserting said system into the interior of said

- 5 cabinet and then passing it partially through a wall of the cabinet, and a baffle attached to said cabinet adjacent to that part of said system which extends into the interior of said cabinet in such manner that in the event of said system becoming loosened from said cabinet said baffle will prevent said system from falling into and damaging the interior of said cabinet.
10. In a refrigerator cabinet, a removable unit refrigerating system including an evaporator, a baffle pan disposed below and in front of the evaporator and supported by the cabinet, and a drip storage receptacle suspended from the baffle pan.
15. 11. A refrigerator comprising a cabinet having upper and lower substantially horizontal walls and front and rear walls, said front wall having an access opening therein and one of the horizontal walls also having an opening, a heat insulating closure for the last-mentioned opening, means releasably but hingedly connecting the closure to the cabinet adjacent the rear edge of said second opening, heat absorbing means on that side of the closure next to the space within the cabinet, and heat dissipating means on the opposite side of the closure, said closure and heat dissipating and absorbing means being removable frontwardly through the access opening in the front wall, by swinging the closure vertically and about its hinge connection, into the space within the cabinet and then forwardly moving it through the access opening in the front wall.
20. 12. A refrigerator comprising a cabinet having upper and lower substantially horizontal walls and front and rear walls, said front wall having an access opening and the upper of the horizontal walls having an opening therein, a heat insulating closure for the last-mentioned opening, means releasably but hingedly connecting the closure to the cabinet adjacent the rear edge of the last-mentioned opening, heat absorbing means on that side of the closure next to the space within the cabinet, and heat dissipating means on the opposite side of the closure, said closure and heat dissipating and absorbing means being removable frontwardly through the access opening in the front wall, by swinging the assembly downwardly about the hinge connection and into the space within the cabinet, and then forwardly moving it through the access opening in the front wall.
25. 13. A refrigerator comprising a cabinet having an opening in one of its walls, a closure for such opening, means hingedly connecting the closure to the cabinet adjacent one edge of the opening, heat dissipating means on the outer side of the closure, heat absorbing means on the inner side of the closure, a spring pressed latch for normally and releasably holding the closure in its closing relation to the opening, and secondary means for holding the closure in a closed position in the event the latch fails to function.
30. 14. A refrigerator comprising a cabinet having an opening in one wall thereof, a closure for such opening, heat dissipating means on the outer side of the closure, heat absorbing means on the inner side of the closure, and means within the cabinet and hingedly connecting the closure to a wall of the cabinet so as to permit swinging movement of the closure and heat absorbing and dissipating means thereon into the space within the cabinet, said hinging means being located in substantially spaced relation to the plane of the opening and the closure when the latter is in closed position, so as to prevent interruption to the normal swinging action of the closure by engagement of the heat absorbing means with a wall of the cabinet.
35. 15. A refrigerator comprising a cabinet having upper and lower walls, one of said walls having an opening therein, a closure for such opening, heat absorbing means on that side of the closure next to the space within the cabinet, heat dissipating means on the other side of the closure, means with the cabinet and hingedly connecting the closure to a wall of the cabinet, substantially in alignment with the inner extremity of the heat absorbing means when the closure is in its closing position, whereby upon swinging the closure about its hinging axis, the heat absorbing means normally will not engage a wall of the cabinet and interrupt the normal swinging action.
40. 16. A refrigerator comprising a cabinet having an opening in one of its walls, a closure for such opening, means hingedly connecting the closure to the cabinet for swinging movement from its closed position into the interior of the cabinet, heat dissipating means on the outer side of the closure, heat absorbing means on the inner side of the closure, releasable latching means for normally holding the closure in closing relation to the opening, and secondary means for holding the closure in its closed position in the event the first latching means fails to function.
45. 17. In combination, a refrigerator cabinet, a removable refrigerating system installed in said cabinet, an electrical circuit leading to said system and including contactors on the cabinet, and a temperature responsive switch in and mounted on the removable system, a housing for the switch, and exposed electrical contactors on the housing and connected to the switch, said last mentioned contactors mating with and adapted to be releasably connected to the first contactors.

GLENN MUFFLY.
